UNITED STATES PATENT OFFICE.

CHARLES GILBERT HAWLEY, OF CLEVELAND, OHIO, ASSIGNOR TO LOCOMOTIVE FIRE-
BOX COMPANY, OF CHICAGO, ILLINOIS, A CORPORATION OF DELAWARE.

LOCOMOTIVE BOILER.

Application filed April 8, 1926. Serial No. 100,482.

This invention relates to improvements in locomotive boilers and it consists of the matters hereinafter described and more particularly pointed out in the appended claims.

5 The primary object of the invention is to provide a simple and efficient means directly associated with the crown sheet and flue sheet of the boiler which operates in that part of the fall in boiler water level, initially uncovering or exposing a part of said crown sheet adjacent the flue sheet, to limit the same to an area which is safe in practice but will act to permit a leakage of a small amount of steam into the firebox, sufficient to be observed in the stoking of the firebox, thereby informing the fireman of the actual water level in the boiler irrespective of the level indicated by the usual water gages.

20 A further object of the invention is to provide in the crown sheet, between predetermined rows of stay bolts channels which extend longitudinally of the crown sheet and act as the water level falls to uncover the high spot or head of the crown sheet at the flue sheet end to limit such spot or area to one of small dimensions and about the stay bolts of which steam escapes into the firebox to be observed by the one stoking the firebox.

25 These objects of the invention as well as others, together with the many advantages thereof will more fully appear as I proceed with my specification.

In the drawings:

30 Fig. 1 is a longitudinal vertical sectional view through the firebox end of a locomotive boiler embodying my invention.

35 Fig. 2 is a vertical transverse section through the same as taken on the line 2—2 of Fig. 1.

40 Fig. 3 is a detail horizontal sectional view on an enlarged scale as taken on the line 3—3 of Fig. 1.

45 Fig. 4 is a detail vertical sectional view as taken on the line 4—4 of Fig. 3.

50 Referring now in detail to that embodiment of the invention illustrated in the accompanying drawings:—1 indicates the back or door sheet of the firebox and 2 indicates the flue sheet thereof and forming a continuation of the flue sheet, is the inside throat sheet 3. The sides of the firebox are formed by the side sheets 4—4 and the top of the firebox is formed by the transversely 55 arched or curved crown sheet 5 which

merges into the firebox side sheets 4—4. Said side sheets and crown sheet extend between and are connected at their ends to the back sheet 1 and flue and throat sheets 2 and 3 respectively, the crown sheet being inclined upwardly from the back sheet toward the flue sheet so that its highest end or head 6 is at the flue sheet end thereof.

55 The wrapper of the boiler includes a roof sheet 7, a back head 8, outer firebox sheets 9—9 and an outer throat sheet 10 together with a boiler shell 11, all in the manner well known. The front and rear water legs 12 and 13 and the side water legs 14—14 are all closed at the bottom by a mud ring 15, while the bottom of the firebox is formed by the grate indicated by the dotted line 16 in Fig. 1. In the back head and back sheet respectively is formed the fuel door opening 17 and extending forwardly from the flue sheet 2 are the flues or tubes 18 through which the products of combustion from the firebox are drawn to the smoke box at the front end of the boiler (not shown) in the manner well known. The roof sheet and crown sheet are connected by the usual stay bolts 19 as are the side sheets 4 and 9, throat sheets 3 and 10 and back sheets 1 and 8 respectively. The construction just described is typical of that type of locomotive boiler now in general use and need not be described in greater detail.

60 In locomotive practice the usual water level desired to be maintained, is such as to keep the crown sheet submerged at all times. However, due to the amount of water generated into steam for the intended purpose of the locomotive, the water level falls. Gage glasses in the cab are intended to indicate the levels of the water but such devices are often inaccurate, not always due to any faulty construction therein, but to certain boiler conditions such as surges and foamings which will produce in the gage glasses, levels which do not correspond to the actual water level in the boiler. When the real water level falls below that point, good locomotive practice demands be maintained, the first part of the crown sheet to be uncovered thereby, is that point of highest elevation and which point is usually the head 6 of the crown sheet, which is located in the longitudinal median plane of the transversely curved crown sheet. Such a level as will uncover or expose this part of the 110

crown sheet is best indicated at 20 in Figs. 1 and 4.

To maintain or limit the uncovered or dry area of the crown sheet to one of as small dimensions as possible, I form in the crown sheet, longitudinal V-shaped channels 21-21, one on each side of and adjacent the median plane of the crown sheet, said channels increasing in width and depth 10 from the rear toward the front where each channel terminates in an inclined front wall 22 adjacent the crown sheet, the bottom of each channel being arranged in a horizontal plane. A conduit or short pipe section 23 arranged in the firebox, opens through the front end wall of each channel and flue sheet as best shown in Fig. 4.

As the water level recedes so as to uncover the head end of the crown sheet, 20 where it is highest in elevation, the lateral edges of said uncovered and dry spot will be defined by portions of the channels which are filled with water, the conduits 23 preventing the trapping of the water at the 25 front end of each channel and permitting a better circulation of boiler water in this vicinity. The front end of said dry spot is defined by the front edge of the crown sheet, the rear edge of the dry area is defined by 30 the water edge as best shown in Fig. 3 so that said dry spot is one of such area as may be uncovered with safety.

That part of the crown sheet, thus uncovered becomes exceedingly hot and will flex 35 inwardly of the firebox, thus pulling away from the stay bolts 19 within said dry spot or area so that steam will escape in small quantities about said stay bolts into the firebox. Such a condition is instantly visual-

ized by the fireman who will feed more water into the boiler to submerge the crown sheet head. With the entire crown sheet submerged the danger of complete fracture thereof is eliminated but the locomotive is withdrawn from service at the first opportunity.

The channels in the crown sheet not only thus act to define or limit the sides of said dry area but at the same time act to rigidify the crown sheet as is apparent.

While in describing my invention I have referred to certain details of construction as well as form and arrangement of the parts thereof, I do not wish to be limited thereto except as may be pointed out in the appended claims.

I claim as my invention:

1. A locomotive boiler embodying therein, a firebox including a crown sheet and a flue sheet, said crown sheet being formed to provide channels therein terminating short of the flue sheet and a conduit opening at one end into the channel and at its other end through the flue sheet.

2. A locomotive boiler embodying therein, a firebox including a stay bolted crown sheet and a flue sheet, said crown sheet being formed to provide longitudinal channels therein between adjacent rows of stay bolts, which channels increase in width and depth 70 from the rear toward the front where they terminate in an inclined front wall adjacent the flue sheet and a conduit fixed at its ends in the front wall of each channel and in said flue sheet respectively.

In testimony whereof, I have hereunto set my hand, this 5th day of April, 1926.

CHARLES GILBERT HAWLEY.
